UNITED STATES PATENT OFFICE.

JOHAN FREDERIK PETRUS SCHÖNFELD, OF HILVERSUM, NETHERLANDS, ASSIGNOR OF ONE-HALF TO N. V. DE BATAAFSCHE PETROLEUM MAATSCHAPPIJ, OF THE HAGUE, NETHERLANDS.

SEPARATING CONGEALABLE SOLIDS FROM OILS.

Application filed March 12, 1925, Serial No. 15,117, and in the Netherlands March 24, 1924.

The invention relates to a process of separating solids from mineral, animal or vegetable oils and fats or mixtures thereof, especially of separating paraffine from paraffine containing oil.

As a rule a paraffine containing oil is separated as much as possible into its components by means of crystallization, as compound crystals may exist of oil and paraffine in all possible proportions. This crystallization takes place in most cases in such a way that the mixture is repeatedly heated or cooled to certain temperatures after which the liquid is separated from the crystals as much as possible. As a matter of fact this process goes on very slowly, if at any rate a somewhat complete separation of the paraffine and the oil is to be obtained.

It has already been proposed to accelerate the process by spraying the liquid paraffin containing oil with water of lower temperature, in which a distribution of the oil to drops takes place and the mass is subjected in this condition to the cooling action of the water; a part of the oil will then more or less proceed to solidification subject to the temperature of the oil and of the water, and may be separated from the rest.

In carrying out this process one proceeded as follows: The liquid oil was led through a jet-pipe into a container and at the same time the water was fed through a conduit arranged around the jet-pipe for the oil. The paraffin particles having the highest melting point solidified nearly immediately and floated to the surface of the liquid. They could then be easily separated from the oil which was removed with the water from the container.

Although in the beginning great expectations were had about this process it has not satisfied in practice so that soon it fell into disuse. This unfavourable result must be ascribed chiefly to the fact that the paraffin by the cooling action of the water will first solidify at the periphery of the drops, whereby the oil is enclosed in these drops and later on no partial solidification may take place. Therefore only a very incomplete separation of the paraffin and removal of the oil with lower melting point takes place so that for obtaining a somewhat favourable result it is necessary to melt repeatedly the solidified paraffin and to spray it again. The repeated

melting of the paraffin requires much vapour and in great part nullifies the speed of working aimed at.

Another disadvantage is that the process cannot be carried out continuously.

The invention now enables one to accelerate the process considerably and at the same time to obtain a rather complete separation of the required kinds of paraffin as has been proved irrefutably by experiments.

The process according to the invention now consists therein that the oil, the fat or the mixture is atomized in an atmosphere of lower temperature and the atomized mass soon after leaving the atomizer is brought close to water which is also atomized.

The invention also comprises a process in which the removal of the liquid phase begins immediately after the atomizing.

The process will be carried out preferably by atomizing the paraffin containing oil in air. By the atomizing, a very fine division of the oil is obtained which is much finer than is possible when spraying the oil into water. It causes the paraffin with a certain specific weight to separate practically fully in the extremely small particles of oil. By the application of the water as a fog a very quick transmission of the heat is obtained from the oil via the air to the water fog, by which the output of paraffin of the desired low specific weight is much more favourable in connection with the chosen circumstances than in the known processes.

I proceed for instance as follows:

On the delivery pipe of the oil to be treated one or more atomizers are arranged by which the oil may be atomized in a closed room which, for regulating the temperature, may be ventilated. Preferably I take care that the temperature of the oil when leaving the atomizers is about 3/10° C. higher than its solidifying point.

By means of a second delivery pipe with atomizers water is atomized. The atomizers for the oil and the water are so arranged that the fog of oil and that of water meet at some distance from the atomizing mouths. The fine drops of paraffin, which are for the greater part solidified, after rising fall on a sieve bottom where the paraffin sticks together and forms a porous layer, the oil flowing off through it.

For continuously carrying out the process

it is recommendable to arrange the sieve bottom with some inclination. The layer or paraffin so obtained moves slowly downward on the inclined bottom and may be led 5 out of the work-room. At the same time the favourable result is obtained that in the mass channels arise in longitudinal direction through which the oil penetrates through the layer of paraffin and flows away through 10 the sieve bottom.

The accompanying drawing shows in Fig. 1 a vertical section of an installation for applying the new process.

Fig. 2 is a cross-section on the delivery 15 pipes along the line II-II in Fig. 1.

In the work-room 1 the delivery pipe 2 for the paraffin containing oil is arranged which is provided with the atomizers 3. Under it the perforated bottom 4 is found 20 on which the solid paraffin slowly slides down to the channel 5, the oil which has remained liquid flowing through it and on the bottom 6 to the conduit 7. The second delivery pipe 8 provided with atomizers 25 serves for supplying the water which is also atomized. Both fogs get into touch at some distance above the mouths of the atomizers.

The whole work-room, especially the sieve bottom 4, is arranged with some inclination, 30 openings 11 and 12 being arranged preferably at the front and the back so that if desired a quick ventilation of the work-room may take place.

The solid paraffin arrives in the container 35 13 with steam-conduit in which it is melted for further treatment, the liquid oil is

caught in the container 14 from where it may once more be atomized for depositing paraffin which then however has a lower melting point than that which was first 40 separated. Also in this container 14 a deposit of paraffin takes place from the foam coming therein.

It is clear that the melting point of the paraffin obtained in this way is dependent 45 upon the temperature of the paraffin containing oil, the speed by which it is atomized and the temperature of the atomized water. The conditions of working are chosen in connection with the nature of the material 50 and the environment and also with the nature of the product which is desired to be obtained.

I claim:

1. The process of separating congealable 55 solids from mineral, animal, vegetable or paraffin oils containing them which comprises atomizing the oil in a cool atmosphere containing a fog of water particles.

2. The process of separating solidifiable 60 matter from oils containing them in un-solidified condition which comprises atomizing oil of the character stated into an atmosphere containing a fog of water particles at a temperature sufficiently low to 65 produce congelation of said substances in said atomized particles and thereafter separating un-congealed material from that which is congealed.

In testimony whereof I affix my signature.

JOHAN F. P. SCHÖNFELD.
